Attorney, Agent, or Firm—Cumpston & Shaw

[57] CLAIM

The ornamental design for a toy periscope, substantially as shown and described.

DESCRIPTION

FIG. 1 is a perspective view of a toy periscope showing
my new design;

FIG. 2 is a right side elevational view thereof;

FIG. 3 is a rear elevational view taken in the direction of arrows 3—3 in FIG. 2; and

FIG. 4 is a bottom plan view thereof.
